UNITED STATES PATENT OFFICE.

CLEARMONT V. BEST, OF CANTON, OHIO.

DESIGN FOR AN INCANDESCENT VAPOR-BURNER FRAME.

SPECIFICATION forming part of Design No. 32,361, dated March 20, 1900.

Application filed February 16, 1900. Serial No. 5,539. Term of patent 7 years.

To all whom it may concern:

Be it known that I, CLEARMONT V. BEST, a citizen of the United States, residing at Canton, in the county of Stark and State of Ohio, 5 have invented and produced a new and original Design for an Incandescent Vapor-Burner Frame, of which the following is a specification, reference being had to the accompanying drawings, forming part thereof.

- o Figure 1 is a side elevation. Fig. 2 is an edge view. Fig. 3 is a side elevation showing the opposite side from that illustrated in Fig. 1. Fig. 4 is an edge view showing the opposite edge from that illustrated in Fig. 2.
- 5 As shown in the drawings, the leading or material feature of my design consists in two parallel bars 1 and 2, spaced one from the other throughout their length, the bar 1 being formed somewhat larger than the bar 2 and the two parallel bars connected at their bottom or lower ends by means of a horizontal or cross bar 3, from which cross-bar is extended the bar 4, said bar 4 being extended at right angles to the cross-bar 3. To one 5 side of the parallel bar 2 is extended the bar 5, said bar being located about midway between the connected ends of said bar. From the bar 1 extends the flanged arm 6, and from one side of the arm 6 extends the fin 7, which 10 fin extends downward from the arm 6 to a point nearly opposite the bar 3. At the outer edge

of the fin 7 and upon its upper outer portion is located the flange 8, which flange extends from and is connected with the arm 6. From one side of the bar 1 and above the arm 6 is located the lateral extension 9, said lateral extension increasing in width from its upper end downward and terminating at a point located at one side of the arm 6, as illustrated in Fig. 2. Directly below the lateral extension 9 is located the fin 10, which fin terminates upon the upper side of the arm or stud 11.

At the upper ends of the parallel bars 1 and 2 is located the enlarged head 12, which enlarged head is provided with a flange 13, formed upon the bottom or lower end thereof and located substantially as shown in the drawings.

Having fully described my invention, what 50 I claim as new, and desire to secure by Letters Patent, is—

The design for an incandescent vapor-burner frame, as shown and described.

In testimony that I claim the above I have 55 hereunto subscribed my name in the presence of two witnesses.

CLEARMONT V. BEST.
